United States Patent Office.

ANDREW C. BLACK, OF KAUKAUNA, WISCONSIN.

Letters Patent No. 92,570, dated July 13, 1869.

IMPROVEMENT IN LAMP-CRANES.

The Schedule referred to in these Letters Patent and making part of the same.

To all whom it may concern:

Be it known that I, ANDREW C. BLACK, of Kaukauna, in the county of Outagamie, in the State of Wisconsin, have invented a new and useful device for the support and adjustment of hanging lamps, which I call a Lamp-Crane; and I do hereby declare the following to be a full and correct description of the same, reference being had to the accompanying drawings, in which—

Figure 1 is a perspective view of my lamp-crane complete, attached to the ceiling of a room.

Figure 2 is a side elevation, and

Figure 3, a bottom view of the same.

The same letter indicates the same part in the several figures.

The invention consists of a suspended, swivelling crane, on any part of the arm of which a lamp may be hung, and said arm turned around an entire circle, the object being to provide a simple, convenient, and inexpensive device for giving to a suspended light any desired position in the apartment in which it is used.

In the accompanying drawing—

A marks a board, to which the crane-swivel is attached.

This board is to be attached, by screws *a a*, to the ceiling of the apartment in which the crane is to be used.

To it is attached the swivel-hook *s* by the headed pin *e*, on which the swivel turns freely around the entire circle.

In this hook is hung, by pivot *p*, the crane *B*, which has one short and one long arm.

On the end of the short arm is an axle, *b*, which receives a wheel or roller, *C*, the periphery of which rests upon the under surface of the board *A*.

This roller facilitates the swivelling of the crane *B*.

A rack, *R*, formed of wire, so bent as to make a series of hooks, *h h*, as shown, and having the outline of a circular arc, serves as a means of attachment for the lamp, and also for adjusting its height above the floor.

The curved form of the rack keeps its lower end out of the way of the lamp, however high on the rack the lamp may be suspended.

When the rack is long, it is preferable to make it in two or more sections.

The operation is obvious:

The lamp may be hung at any height, in the centre of the room, or at any distance from the centre, admitted by the length of the arm *B*, which may extend to the side of the room, if desired.

By changing the distance of the lamp from the centre on the arm *B*, and by turning that arm, the lamp may be brought over any point in the area of the circle of which the long arm of the crane is the radius.

What I claim, and desire to secure by Letters Patent, is—

A lamp-crane, consisting of an arm or lever suspended from the ceiling of a room by a swivel-joint, so as to be capable of movement around an entire circle, and having a wheel on one end to facilitate its motion, and supporting the lamp at any desired point on the other end, substantially in the manner and for the purpose hereinbefore set forth.

The above specification of my said invention signed and witnessed at Washington, this 27th day of April, A. D. 1869.

A. C. BLACK.
